UNITED STATES PATENT OFFICE.

JOHN CLULEE, OF WALLINGFORD, CONNECTICUT, ASSIGNOR TO SIMPSON HALL MILLER & COMPANY, OF SAME PLACE.

DESIGN FOR A HANDLE FOR SPOONS, &c.

SPECIFICATION forming part of Design No. 23,171, dated April 10, 1894.

Application filed March 12, 1894. Serial No. 503,367. Term of patent 3½ years.

I. all whom it may concern:

Be it known that I, JOHN CLULEE, of Wallingford, in the county of New Haven and State of Connecticut, have invented a new Design for the Handles of Spoons, Forks, &c.; and I do hereby declare the following, when taken in connection with the accompanying drawing and the letters of reference marked thereon, to be a full, clear, and exact description of the same, and which said drawing constitutes part of this specification and represents a face view.

This invention relates to a design for the handles of spoons, forks, &c., and the design consists in the configuration and ornamentation as shown in the accompanying illustration.

As herein shown the handle gradually expands from the bowl to the tip. The face of the handle is ornamented by a narrow border A, of reverse scrolls, lying upon and overlapping straight ribs B, the scrolls at the top growing more elaborate, and separated from

the ribs by a floriated ornamentation C, and meeting in a shell ornament D, forming the 25 tip, and overlying a conventionalized flower form E. The scrolls at the narrower part of the handle converge and form an intricate scroll and shell ornamentation, extending down upon the handle, the scrolls inclosing 30 and overlapping upon a plain panel F. At the junction of the handle and bowl there is a similar scroll work extending upward on the handle, all as shown in the accompanying illustration.

35

I claim—

The design for the handles of spoons, forks, &c., as herein shown and described.

In testimony whereof I have signed this specification in the presence of two subscribing witnesses.

JOHN CLULEE.
